UNITED STATES PATENT OFFICE.

CHRIST BENKER, OF PITTSBURG, PENNSYLVANIA, ASSIGNOR OF ONE-HALF
TO EBENEZER B. MATTHEWS, OF SAME PLACE.

MACHINE FOR FORMING SKELP-IRON.

SPECIFICATION forming part of Letters Patent No. 398,120, dated February 19, 1889.

Application filed February 27, 1888. Serial No. 265,483. (No model.)

To all whom it may concern:

Be it known that I, CHRIST BENKER, of Pittsburgh, in the county of Allegheny and State of Pennsylvania, have invented a new and useful Improvement in Machines for Forming Skelp-Iron; and I do hereby declare the following to be a full, clear, and exact description thereof, reference being had to the accompanying drawings, forming part of this specification, in which—

Figure 1 is a plan view of my improved device for forming skelp-iron. Fig. 2 is an end elevation of the same. Fig. 3 is a vertical longitudinal section on the line *x x* of Fig. 2. Fig. 4 shows sectional views of the blank before and after it passes through various parts of the device.

Like letters of reference indicate like parts in each.

20 In the drawings, 2 represents the main power-shaft, which is provided with a belt or gear wheel, 3, by which power is applied to the shaft. Keyed to the shaft 2 is a toothed wheel, 4, and a toothed wheel, 5, the first of which, 4, gears with a toothed wheel, 6, on the shaft 7, while the toothed wheel 5 gears with a wheel, 8, which is loosely mounted on a shaft, 9, situate directly below the shaft 7. Mounted on the shaft 9 by a feather and spline 25 or other similar device is a clutch-wheel, 10, having projecting spurs 11, which are adapted to engage with recesses in the side of the wheel 8, the clutch-wheel 10 being arranged to slide on the shaft 9 and to be thrown in and out of gear by means of the pivoted arm 12 and foot-lever 13.

Keyed to the shaft 7 is a grooved roller, 14, in the groove of which a tongue-roll, 15, fits, which roll is keyed to a shaft, 16, and on which 30 shaft is a toothed wheel, 17, which gears with the toothed wheel 6 on the shaft 7.

The shafts 9 and 16 are connected together by cam crank-arms 18, while the shaft 16 is mounted in sliding boxes 19, which fit in suitable vertical ways in the frame-work or housings 20, the purpose of the crank-arms 18 being to elevate and lower the tongue-roll 15. In the rear of the tongue and groove rolls 14 and 15 is a U-shaped die, 21, having a central 45 core, 22, to the rear face of which the mandrel

or core-rod 23 is attached. Situate below the core-rod 23, mounted on the shaft 24, is a roller, 25, having a flange on one side, 26. Above the core-rod 23, keyed to a shaft, 27, is a similar roller, 28, having a similar flange, 29. 55 The two shafts 24 and 27 are connected by the two gear-wheels 30 31.

In rear of the rollers 25 and 28 are two rollers, 32 and 33, having flanges 34 on both sides, which form a central groove above and below 60 the mandrel. These rollers are mounted on shafts 35 and 36, which are connected with each other by gear-wheels 37, similar to the gear-wheels 30 and 31. Power is applied to the shafts 24 and 35 from the shaft 7 by means 65 of the sprocket-wheels 38, 39, and 40 and a chain, 41, the chain being guided by the roll 42. The rollers 32 and 28 are journaled in sliding bearings in the housings 20 and are provided with screws 43, by means of which 70 the position of the rolls above the mandrel may be regulated.

The operation is as follows: Power being applied to the shaft 2, the heated blank in the form shown in the first part of Fig. 4 is drawn 75 from the furnace and fed between the rollers 14 15. At this time the foot-lever 13 is depressed, which throws the clutch 10 into gear with the toothed wheel 8, which wheel 8 is geared with the wheel 5 on the shaft 2. This 80 imparts power to the shaft 9, causing it to revolve, and thereby, by means of the crank-arms 18, elevates the shaft 16 and the tongue-roll 15, which permits the heated blank to pass between the tongue and grooved rolls 14 85 15. On the side of the wheel 8 is a cam, 45, which by the revolution of the wheel comes in contact with the lever-arm 46, which is connected with the foot-lever 13 and lever-arm 12, and also with the clutch 10, and throws 90 the arm 46 back, which releases the clutch 10 from the wheel 8, at which time the crank-arms 18 have brought the tongue-roll down on the blank which has been inserted between the rollers 14 and 15. These rollers by their 95 revolution—the roller 15 being caused to rotate by the gear-wheel 17—feed the blank forward, and at the same time bend it into the shape shown in the second part of Fig. 4. After passing the rollers 14 15 it enters the 100

die 21 about the mandrel 23, and passes under the rolls 25 29, the flanges of which bend the blank around the mandrel into the shape shown in the third part of Fig. 4. The skelp 5 then passes between the rollers 32 33, the flanges of which bend the blank into the shape shown in the fourth part of Fig. 4, thus forming the completed skelp.

The advantages of my improvement are, 10 that the skelp is rapidly formed without the trouble of drawing, as in the method employed heretofore. It is first bent, instead of twisted, into a regular **U** shape, and then further bent about a central mandrel, which gives the skelp 15 an even and regular shape.

Having thus described my invention, what I claim, and desire to secure by Letters Patent, is—

1. In a machine for forming skelp-iron, the 20 combination of tongue and groove rollers, a mandrel, a pair of single-flange rollers at one end of the mandrel, and a pair of double-flanged rollers at the other or delivery end, the mandrel being arranged between the upper and lower members of the two pairs of 25

rollers and sustaining the skelp as it is formed about it by the rollers, substantially as described.

2. In a machine for forming skelp-iron, the 30 combination of tongue and groove rollers, a shaft for the tongue-roller, movable bearings for said shaft, and crank-connections for said shaft, with a rotary shaft periodically to raise and lower the tongue-roller shaft, substantially as described.

3. In a machine for forming skelp-iron, the 35 combination of a grooved roller, a tongued roller mounted on a vertically-movable shaft, cam crank-arms connected with the movable shaft, a power-shaft, a clutch for connecting the power-shaft with the power mechanism, and a cam for throwing the clutch out of gear, substantially as and for the purposes specified.

In testimony whereof I have hereunto set my hand this 27th day of January, A. D. 1888. 45

CHRIST BENKER.

Witnesses:

W. B. CORWIN,
J. K. SMITH.
